UNITED STATES PATENT OFFICE.

SOLOMON KAUFMAN, OF NEW YORK, N. Y.

WRIST-WATCH CONTAINER.

1,205,217.

Specification of Letters Patent. Patented Nov. 21, 1916.

Application filed April 29, 1916. Serial No. 94,335.

To all whom it may concern:

Be it known that I, SOLOMON KAUFMAN, a citizen of the United States of America, residing in the city of New York, county of Bronx, and State of New York, have invented certain new and useful Improvements in Wrist-Watch Containers, of which the following is a specification.

This invention relates to and has for an object to provide means for securely incasing a watch and holding this in its case when applied to the person of the wearer, as for instance, to the wrist.

In the preferred form of the invention a plate is normally held more or less securely to the back of the casing and is locked in its proper position relatively thereto by the wrist encircling means, as for instance, the strap.

In the drawings accompanying this application, one practicable embodiment of the invention is illustrated, in which drawings—

Figure 1 is a top view; Fig. 2 is an underside view of that side which is in engagement with the wrist when the watch is in position thereon; Fig. 3 is a longitudinal sectional taken on a plane at about the line 3—3 of Fig. 1; and Fig. 4 is a cross section taken on about the plane of the line 4—4 of Fig. 1.

The form, size and dimensions of the container are determined by its intended use and in some instances by the material of which constructed. In the illustration the casing 5 which is the outer member when the container is secured in position on the wearer, presents a plain surface and is of substantially elliptical contour, provided in the center with an opening 6 through which the dial of the watch is visible. The underside of the casing (see Fig. 3) is curved to conform to the wrist, and the ends are shown provided with openings 7 for receiving a strap or chain. These openings are given a formation which will at once serve the function of receiving either a strap or chain, an outward extension 7' being illustrated for centering the latter. An opening 8 is shown provided at one side for receiving the stem of the watch when this is in position. A plate 9 for closing the back of the casing is illustrated as formed to correspond with the formation of the back or wrist side thereof. This plate is shown held in position by a pair of inturned flanges 10

carried by the sides of the casing, these flanges in the illustration being located in such position that the back plate 9 may readily slide into position under the flanges and be held in position. If the plate is of springy material and slightly flatter than the curvature of the back of the casing, the compression or spring action tends to flex the closure plate and hold the same in position.

For the purpose of locking the closure plate 9 in position on the casing 5 it is shown provided with openings 11 registering with the openings 7 when the plate is in position and through these openings is passed the wrist encircling member, as for instance the strap 12. The strap then not only serves to hold the watch and the container to the wrist of the wearer but also locks the closure in its closed position, and a removal of the container from the wrist does not necessarily entail the release of the closure member unless the strap is intentionally withdrawn from the mating slots 7, 11 at both ends of the structure.

It is understood that the container shown in the drawing is an illustrative example of the invention and that changes may be made within the scope of the claims without departing from the spirit of my invention.

What I claim is:

1. In a watch container, the combination with a casing provided at its front with an opening for exposing the dial of the watch contained therein, the rear wall of said casing being curved inwardly from the ends toward the center, the sides of the casing being provided with inturned flanges, and a curved plate adapted to close the rear of said casing and be engaged by said flanges, and means for locking the closure plate in position.

2. In a watch container, the combination with a casing provided at its front with an opening for exposing the dial of the watch contained therein, the rear wall of said casing being curved inwardly from the ends toward the center, the sides of the casing being provided with inturned flanges, and a curved plate adapted to close the rear of said casing and be engaged by said flanges, the respective ends of the casing and closure plate being provided with registering openings for receiving a strap or the like.

3. In a watch container, the combination

with a casing provided at its front with an opening for exposing the dial of the watch contained therein, the rear wall of said casing being curved inwardly from the ends toward the center, the sides of the casing being provided with inturned flanges, and a curved plate adapted to close the rear of said casing and be engaged by said flanges, the respective ends of the casing and closure plate being provided with registering openings, and a wrist strap located in said registering openings.

4. In a wrist watch container, the combination with a casing provided at its front with an opening for exposing the dial of the watch contained therein, the rear wall of said casing being curved inwardly from the ends toward the center, the sides of the casing adjacent the said center portion being provided with inturned flanges, and a plate adapted to close the rear of said cas-

ing and be engaged and flexed by the said flanges.

5. In a wrist watch container, the combination with a casing provided at its front with an opening for exposing the dial of the watch contained therein, the rear wall of said casing being curved inwardly from the ends toward the center, the sides of the casing adjacent the said center portion being provided with inturned flanges, a plate adapted to close the rear of said casing and be engaged and flexed by the said flanges, and means for locking the closure plate in position.

In witness whereof, I have hereunto signed my name in the presence of a subscribing witness.

SOLOMON KAUFMAN.
